CLOSURE FOR RECEPTACLES

Charles S. Baron, Tiffin, Ohio

Application July 6, 1938, Serial No. 217,757

15 Claims.

(Cl. 65—31)

The present invention relates to an improved closure for receptacles such as syrup pitchers, sugar jars and containers for various other liquid and solid substances.

An essential feature of the invention is to provide a simple, efficient and economical cap or closure for a receptacle, in which either a one-piece or a two-piece cap has associated with a discharge opening in the top thereof, a displaceable member having one of its end portions formed to constitute a flap for closing the discharge opening, and its opposite end portion shaped to provide a thumbpiece for actuating the flap. The displaceable member is pivotally connected to the cap by a hinge plate or retaining member which extends through an elongated slot in the top of the cap. The hinge plate also has an offset portion projecting above the cap which is in overlapping engagement with an intermediate portion of the displaceable member so as to be rigidly secured thereto by any suitable retaining means. The hinge plate loosely extends through the slot in the top and coacts with the wall thereof to constitute a fulcrum support for the displaceable member. The invention is also an improvement over the receptacle closure embodied in my Patent No. 2,102,349, dated December 14, 1937 in that it reduces to a minimum the number of essential parts required to efficiently operate the flap to permit the discharge of the contents of the receptacle therefrom.

A further object consists in associating with the hinge plate connected to the displaceable member, yieldable means which engage the underside of the top of the cap so as normally to maintain the flap in its closed position relative to the discharge opening in the top.

Another object consists in rotatably connecting a handle to the receptacle so that the handle may be turned to align with a thumbpiece on the cap when the latter is applied to the receptacle.

Other objects and advantages of the invention will become apparent from the following description when taken in conjunction with the accompanying claims and drawings.

Referring to the drawings in which are disclosed several preferred embodiments of the invention:

Figure 1 is a side view of a receptacle showing a two-piece cap constructed in accordance with the invention and with parts in section for the purpose of illustration.

Figure 2 is a sectional view taken substantially along the line 2—2 of Figure 1 and looking in the direction of the arrows.

Figure 3 is a sectional view taken substantially along the line 3—3 of Figure 1.

Figure 4 is a sectional view taken substantially along the line 4—4 of Figure 1.

Figure 5 is a side view of a modified form of the invention with parts in section.

Figure 6 is a sectional view taken substantially along the line 6—6 of Figure 5.

Figure 7 is a sectional view of a further modification showing a one-piece cap with my invention applied thereto.

Figure 8 is a sectional view taken substantially along the line 8—8 of Figure 7.

Figure 9 is a sectional view taken substantially along the line 9—9 of Figure 7.

Figure 10 is a disassembled perspective view of the displaceable member and the hinge plate showing a double coil spring carried by the plate.

Figure 11 is a sectional view of another modification.

Figure 12 is a side view of the neck of the receptacle showing the retaining means for applying a one-piece cap thereto.

Figure 13 is a sectional view of another modification of the invention.

Figure 14 is a plan view of Figure 13.

Figure 15 is a side view of a receptacle with my improved cap applied thereto and having a rotatable handle connected to the neck of the receptacle.

Figure 16 is a sectional view taken substantially along the line 16—16 of Figure 15.

Referring to the drawings, in which like numerals indicate like parts in the several views, 15 (Fig. 1) designates a dispensing receptacle, such as a glass pitcher, jar or the like, of any suitable shape and material, for receiving syrup, sugar and various other solid and liquid substances so as to constitute a readily portable and sanitary container therefor. The receptacle 15 may have an externally threaded neck 16 for receiving a complementary threaded collar or skirt 17 of a two-piece metallic cap or closure 18. The collar 17 has an inwardly extending annular flange 19 which engages a complementary flange 20 on the upper section 21 of the cap so that when the collar is applied to the receptacle, the section 21 is maintained firmly in position. A liner 22 of any suitable gasket material may be interposed between the mouth of the receptacle and the flange 20 to provide a hermetical seal at the mouth when the cap is initially applied. The upper section 21 has its top 23 provided with a pouring opening 24 which is controlled by a displaceable member 25. The displaceable member 25 is pref-

15

55

erably shaped to provide a flat end portion 26 which constitutes a flap or lid for normally closing the discharge opening 24 and has its opposite end portion shaped to provide a thumbpiece 27 which registers with a handle 28 on the receptacle 15. The flap 26 is connected to the thumbpiece by an upwardly inclined intermediate portion 29 so that the displaceable member constitutes a combined or integral flap and thumbpiece. A hinge plate or retainer member 30 extends loosely through a slot 31 in the top of the cap and has laterally or outwardly projecting arms 32 (Fig. 3) positioned below the top and arranged to engage the underside thereof to prevent the upward removal of the plate from the cap. The plate 30 immediately above the slot 31 is bent to provide an offset portion 33 which extends parallel with the intermediate portion 29 of the displaceable member so as to overlap and engage the same. The displaceable member may be secured to the hinge plate by a rivet 34 which extends through the intermediate portion 29 and the offset portion 33. The sides of the intermediate portion 29 may be formed with flanges 35 which engage the adjacent sides of the offset portion 33 of the hinge plate to prevent lateral movement of the displaceable member relative to the hinge plate and which also insures the flap 26 when in its closed position, being maintained to overlap the opening 24.

The juncture of the hinge plate 30 with its offset portion 33 coacts with the walls of the slot 31 to constitute a fulcrum support for the hinge plate and the displaceable member, so as to permit the convenient raising of the flap 26 when the thumb piece 27 is depressed. The flanges 35 on the displaceable member project slightly beyond the side walls of the slot 31 to limit the downward movement of the plate when the same is connected to the displaceable member. Thus, the plate 30 is movably connected to the cap by the arms 32 and the flanges 35 positioned on opposite sides of the top. (Fig. 3).

As the flap 25 is heavier than the thumbpiece, it will, when pressure is released from the thumbpiece, return by gravity to its normal horizontal position to close the opening 24. As shown in Figure 1, the contents of the receptacle is prevented from being discharged therefrom by the liner 22. The thumbpiece 27 is arranged to align with the handle 28 in substantially the same manner as the two-piece cap structure disclosed in my pending application Serial No. 133,675, filed March 29, 1937, now issued as Patent Number 2,136,123 of November 8, 1938. In other words, when it is desired to pour the contents of the receptacle therefrom, the liner 22 is first removed and the cap is reapplied so that the thumbpiece 27 will be maintained in registration with the handle 28 when the collar 17 is threaded onto the neck of the receptacle.

The modification disclosed in Figures 5 and 6, is substantially similar to that previously described with the exception that instead of providing a rivet to secure the displaceable member to the hinge plate, the intermediate portion 36 of the displaceable member 37 has its sides provided with flexible lugs or flanges 38 arranged to be bent over and inwardly in clamping engagement with the adjacent sides of the offset portion 39 of the hinge plate 40 (Fig. 6). The plate 40 extends through a slot 41 in the top of the cap and has laterally extending arms 42 arranged to engage the underside of the top to prevent the upward removal of the plate from the cap. The displace-

able member is formed at one end with the flap 43 and at its opposite end with the thumbpiece 44 which normally assume the position as shown in Figure 5. The upper end of the offset portion 39 of the hinge plate may be curved at the juncture 5 of the intermediate portion 36 with the thumbpiece to provide reinforcing means 36' for increasing the rigidity of the thumbpiece. Upon the depressing of the thumbpiece 44, the displaceable member 37 is moved about its fulcrum support 10 with the walls of the slot 41, to raise the flap 43 away from the discharge opening 45 in the cap and when this pressure is released, the flap is returned by gravity to close the discharge opening 15.

In the modification disclosed in Figures 7, 8 and 9, a one-piece cap 46 is arranged to be detachably connected to the neck 47 of a receptacle 48, and is preferably formed with a depending smooth skirt portion 49 which engages the 20 neck of the receptacle and is connected to a reduced smooth portion 50 by an annular shoulder 51 arranged to overlap the mouth of the receptacle and provide a seal when the cap is applied. The neck 47 may be provided with spaced oppositely disposed inclined ribs 52 (Fig. 12), which terminate in the stops or shoulders 53 and coact with projections or indentations 54 extending inwardly from diametrically opposite sides of the skirt 49 (Fig. 8) so that upon the application of 30 the cap to the receptacle and the turning of the same, the projections 54 engage and ride the underside of the ribs 52 until the ribs and the cap are brought to rest by the stops 53, thus insuring the cap when applied to the receptacle, 35 being firmly but detachably secured thereto and the thumbpiece being maintained in registration with a predetermined portion of the receptacle such as a handle or the like.

The top 55 of the cap has a discharge opening 40 56 controlled by the flap 57 on the displaceable member 58. The flap 57 at its inner end, is bent upwardly to provide an inclined intermediate portion 59 which terminates in a horizontal portion or thumbpiece 60 disposed substantially parallel with the flap 57 (Fig. 10). A hinge plate 61 extends through a slot 62 in the top and has an offset portion 63 adjacent the slot which engages the inclined portion 59 of the displaceable member 58 above the top and which may be secured thereto by the rivet 64 which extends through the aligned openings 65 and 66 in the displaceable member and the hinge plate respectively. The sides of the intermediate portion 59 may be provided with the flanges 67, similar to the flanges 35 (Fig. 4), and which engage the adjacent sides of the offset portion 63 of the plate to prevent lateral movement of the displaceable member relative to the plate when the parts are set up.

The plate 61 also has outwardly extending projections or arms 68 beneath the top of the cap which are arranged to receive the coils 69 of a double coil spring 70. The ends 71 of the spring engage the underside of the cap so as normally to maintain the flap 57 in its closed position relative to the discharge opening 56. The outer ends of the arms 68 are bent as at 72 to prevent the coils from slipping off the ends of the arms and to hold the coils securely but movably in position. 70 Manifestly, instead of connecting the hinge plate with the displaceable member by the rivet 59, these parts may be readily secured together by omitting the rivet 59 and extending the flanges 65 to overlap the offset portion 63 of the plate in the 75

same manner as shown by the connecting means disclosed in Figures 5 and 6.

When the receptacle is initially filled by the packer, a liner such as 22 (Fig. 1) may be interposed between the cap and the mouth of the receptacle to prevent the escape of the material. When it is desired to use the material, the liner 22 is removed and a gasket 13 may be interposed between the shoulder 51 and the mouth of the receptacle when the cap is reapplied to provide a tight seal. This, however, is not always necessary since the tight frictional engagement of the shoulder 51 with the mouth when the cap is applied has been found in most instances, sufficient to prevent leakage of the material from the receptacle.

In the modification disclosed in Figure 11, a one-piece cap 74 is detachably connected to a receptacle 75 in substantially the same manner as the cap 46 previously described, and has its discharge opening formed with a tubular spout 76 which is provided with an inwardly tapered mouth 77 arranged to be closed by a flap 78 which is connected to the hinge plate 79 by any suitable means, such as the rivet 80. A double coil spring 81 is carried by the arms 82 of the plate 79 and has its ends 82' engaging the underside of the top 83 of the cap in substantially the same manner as the spring 70 previously described, in order to normally maintain the flap 78 against the inwardly inclined mouth 79 of the spout 76. A thumbpiece 84 integral with the flap 78 acts when depressed to move the latter away from the spout 76 to allow the contents of the receptacle to be discharged therefrom. The shape of the spout 76 is such as to facilitate the pouring of the material from the receptacle. Consequently, when the thumbpiece 84 is moved downwardly to raise the flap away from the spout and the pressure is released from the thumbpiece, the flap will close the spout and cut off the flow of the syrup or other fluid so as to prevent the same from dripping off and running down the sides of the cap.

Heretofore, it has been difficult to associate a threaded one-piece cap with the handle on a receptacle so as to align the thumbpiece with the handle or a predetermined portion of the receptacle, since neither the threads on the receptacle nor the threads on the cap can be produced uniformly enough to insure the cap being screwed on the neck in such a manner as always to come to a stop at the same place on the receptacle. Accordingly, in the modification shown in Figure 13, a receptacle 85 having a threaded neck 86 has associated therewith a one-piece cap 87 provided with a discharge opening 88 in the top thereof. A displaceable member 89 has at one end a flap 90 and at its opposite end a thumbpiece 91. The flap 90 is connected to the thumbpiece 91 by an inclined intermediate portion 92 which has its sides provided with inwardly projecting flanges 93 that engage the adjacent sides of the offset portion 94 of the hinge plate 95, firmly to secure the plate to the displaceable member. The plate 95 beneath the top has the reduced outwardly extending arms 96 similar in construction to the arms 68 previously described. A double coil spring 97 connected to the hinge plate through the arms 96, has its ends 98 engaging the underside of the top to normally maintain the flap 90 in its closed position relative to the opening 88. An arm 99 has an upwardly extended curved flange 100 (Fig. 14) engaging the side of the cap adjacent the

thumbpiece 91. The flange 100 may be connected by the spaced rivets 101 to the sides of the cap. A depending handle 102 is connected to the free end of the arm 99 in any suitable manner such as by the screw 102' and is positioned to register with the thumbpiece 91 to permit the convenient operation of the thumbpiece when the receptacle is raised and tilted to discharge the material therefrom.

It will be seen that upon the applying of the 10 cap 87 and its associated parts to the receptacle, the handle 102 will be rotated therewith and will remain at all times in registering position relative to the thumbpiece 91 so that the user, may conveniently operate the thumbpiece 91 15 for the purpose of raising the flap 90 to permit the discharge of the material from the receptacle. This form of cap and handle structure is particularly suitable for use with a receptacle having a threaded neck but no handle and may 20 be conveniently applied to the receptacle in such a fashion as to insure the handle and thumbpiece being in registration to permit the convenient actuation of the thumbpiece when the handle is grasped by the user. If desired, the double 25 coil spring 97 may be omitted and the flap 90 closed by gravity in substantially the same manner as the flap 43 shown in Figure 5.

In the modification disclosed in Figures 15 and 16, a one-piece threaded cap 104 is removably 30 connected to the neck of the receptacle 105 as at 106 and is provided with a displaceable member 107 having a thumbpiece 108 and a flap 109 which are connected by the inclined portion 110. The inclined portion has its sides flanged 35 inwardly as at 111 so as to be secured to the offset portion 112 of the hinge plate in substantially the same manner as shown in Figure 6 or may, if desired, be secured by the fastening means shown in Figure 3. The displaceable 40 member may be closed either by gravity or by connecting a coil spring to the arms of the hinge plate in the manner as shown in Figure 13. A metal band or strap 113 has an annular portion 114 which embraces the receptacle below the 45 threaded neck 106 and which terminates in outwardly parallel disposed arms 115 (Fig. 16), each of which is formed with spaced curved clamping jaws 116 for receiving the reduced portion 117 of a wooden handle or the like 118. The parallel arms 115 are provided with registering openings through which extend a threaded bolt 119 detachably connected to the arms by the nut 120. The strap 113 is of sufficiently yieldable material so that when the nut 120 is withdrawn 50 from the bolt 119, the arms 115 may be sprung apart to permit the removal of the clamping jaws 116 from the handle and the withdrawal of the annular portion 114 from the receptacle. Conversely, upon the applying of the strap to 55 the receptacle, and the jaws to the handle or lifting member 118, the tightening of the nut 120 on the bolt 119 will secure the handle to the jaws 116 and will allow the annular portion 114 to be rotatably connected to the receptacle so 60 that when the cap is screwed down on the receptacle, the band and handle may be turned around on the neck of the pitcher to align with the thumbpiece.

A two-piece cap provided with my displaceable 70 member and hinge plate may be used with a receptacle having a handle and the thumbpiece may be brought in alignment with the handle by means such as disclosed in my copending application Serial No. 133,675. Further, a one-piece 75

cap having my invention applied thereto may be detachably connected to a receptacle of any desired shape and configuration so as to align with a handle on the receptacle by providing the cap with opposed projections which coact with complementary ribs on the neck of the receptacle to insure the thumbpiece aligning with the handle. The cap may equally be used with receptacles not provided with handles by connecting a handle to the cap in a manner as shown in Figure 13. Further, a cap having my improved features associated therewith may be either threaded to a receptacle or otherwise applied thereto. The thumbpiece may be located at any point and after the cap is tightly applied to the receptacle, a rotatable handle connected to the receptacle may be turned to register with the thumbpiece to permit the convenient operation of the flap (Fig. 15). It will be manifest that the gravity closing flap shown applied to the two-piece cap in Figure 1 may be substituted for the spring closure flap on the one-piece cap as shown in several of the other figures and that the displaceable member may be fastened to the hinge plate in the various forms illustrated either by the inwardly disposed flanges shown in Figure 6 or by the rivet and grip pieces disclosed in Figure 10. It will be observed that all the forms of the invention have in common, means for pivotally connecting an integral flap and thumbpiece to the cap above the top by a hinge plate which extends through a slot in the top and constitutes a fulcrum support for the displaceable member. The displaceable member and its hinged connecting means may be conveniently applied to either a one-piece cap or a two-piece cap, and the flap may normally be positioned to close the discharge opening either by gravity or by yieldable means associated with the hinge plate and engaging the underside of the top. In other words, the number of parts associated with the cap for normally maintaining the discharge opening closed, is reduced to a minimum without in any way detracting from the efficient operation of the closure means. While the caps to which the invention is applied, are preferably made of metal, it will be manifest that the caps or closures may be made of Bakelite or any other allied substances. The forms of the invention shown are merely illustrative of preferred embodiments and it will be understood that the various detail features may be interchangeably used with either one-piece or two-piece cap structures and that such changes as fall within the purview of one skilled in the art may be made without departing from the spirit of the invention and the scope of the appended claims.

I claim:

1. A cap for dispensing receptacles having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through the slot and having an offset portion above the top, said plate below the top having outwardly extending arms for limiting the upward movement thereof, and means for connecting the offset portion of the plate to the displaceable member, said plate loosely engaging the walls of the slot to provide a fulcrum support for the displaceable member.

2. A cap for dispensing receptacles having a discharge opening and a slot in the top thereof,

said discharge opening having a spout extending above the top, a displaceable member above the top having an end portion constituting a flap normally positioned to close said spout, the opposite end portion of said member being shaped to provide a thumbpiece for actuating the flap, a hinge plate extending loosely through the slot and having an offset portion above the top, said plate below the top having outwardly extending arms for limiting the upward movement thereof, the intermediate portion of the displaceable member having inwardly disposed flanges engaging the adjacent sides of the offset portion of the plate for securing the displaceable member thereto, said plate loosely engaging the walls of the slot to provide a fulcrum support for the displaceable member.

3. A cap for dispensing receptacles having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through said slot and having an offset portion above the top, said plate below the top having laterally projecting arms for limiting the upward movement of the plate, means for connecting the offset portion of the plate to the displaceable member, said plate loosely engaging the walls of the slot to provide a fulcrum support for the displaceable member, and yieldable means connected to the hinge plate and engaging the underside of the top for normally maintaining the flap in its closed position.

4. A cap for dispensing receptacles having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through said slot and having an offset portion above the top, said plate below the top having laterally projecting arms for limiting the upward movement of the plate, means for connecting the offset portion of the plate to the displaceable member, said plate loosely engaging the walls of the slot to provide a fulcrum support for the displaceable member, and a two-coiled spring having a coil carried by each of said arms and its ends engaging the underside of said top for normally maintaining the flap in its closed position against the top.

5. A cap for dispensing receptacles having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through said slot and having an offset portion above the top, said plate below the top having laterally projecting arms for limiting the upward movement of the plate, means for connecting the offset portion of the plate to the displaceable member, said plate loosely engaging the walls of the slot to provide a fulcrum support for the displaceable member, and a two-coiled spring having a coil carried by each of said arms and its ends engaging the underside of said top for normally maintaining the flap in its closed position against the top, said arms being bent at their outer ends to prevent the withdrawal of the coils therefrom.

6. A cap for dispensing receptacles having a discharge opening and a slot in the top thereof, a displaceable member above the top having an end portion constituting a flap normally positioned to close said opening, the opposite end portion of said member forming a thumbpiece for actuating the flap, said flap and thumbpiece being connected by an intermediate portion extending upwardly from the flap adjacent said slot, a hinge plate extending through said slot and having an offset portion above the top, said plate below the top having laterally projecting arms for limiting the upward movement thereof, and means connecting the offset portion of the plate to the intermediate portion of the displaceable member above the top, said plate loosely engaging the walls of the slot to provide a fulcrum support for the displaceable member.
7. A cap for dispensing receptacles having a discharge opening and a slot in the top thereof, a displaceable member above the top having an end portion constituting a flap normally positioned to close said opening, the opposite end portion of said member forming a thumbpiece for actuating the flap, said flap and thumbpiece being connected by an intermediate portion extending upwardly from the flap, a hinge plate extending through said slot and having an offset portion above the top, said plate below the top having laterally projecting arms for limiting the upward movement thereof, means connecting the offset portion of the plate to the intermediate portion of the displaceable member adjacent the slot, said plate loosely engaging the walls of the slot to provide a fulcrum support for the displaceable member, and yieldable means carried by said arms and engaging the underside of the top for normally maintaining the flap in its closed position against the top.
8. A cap for dispensing receptacles having a discharge opening and a slot in the top thereof, a displaceable member above the top having an end portion constituting a flap normally positioned to close said opening, the opposite end portion of said member forming a thumbpiece for actuating the flap, said flap and thumbpiece being connected by an intermediate portion extending upwardly from the flap, a hinge plate extending through said slot and having an offset portion above the top, said plate below the top having laterally projecting arms for limiting the upward movement of the plate, and the intermediate portion of said displaceable member having inwardly projecting flanges engaging the adjacent sides and the rear of the offset portion of the plate for securing the displaceable member to the plate, said plate loosely engaging the walls of the slot to provide a fulcrum support for the displaceable member.
9. A cap for dispensing receptacles having a discharge opening and a slot in the top thereof, a displaceable member above the top having an end portion constituting a flap normally positioned to close said opening, the opposite end portion of said member forming a thumbpiece for actuating the flap, said flap and thumbpiece being connected by an intermediate portion extending upwardly from the flap, a hinge plate extending through said slot and having an offset portion above the top, said plate below the top having laterally projecting arms for limiting the upward movement of the plate, the intermediate portion of said displaceable member having inwardly projecting flanges engaging the adjacent sides and the rear of the offset portion of

the plate for securing the displaceable member to the plate, said plate loosely engaging the walls of the slot to provide a fulcrum support for the displaceable member, and a double coiled spring having a coil carried by each of said arms and its ends engaging the underside of the top normally to maintain the displaceable member against the top.

10. A cap for dispensing receptacles having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through the slot and having an offset portion above the top, means on the plate below the top for limiting the upward movement thereof, means for connecting the offset portion of the plate to the displaceable member, said plate loosely engaging the wall of the slot to provide a fulcrum support for the displaceable member, and a handle connected to the side of the cap and in substantial alignment with said thumbpiece.

11. In combination with a receptacle having a handle, a cap detachably connected to the receptacle, said cap having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through the slot and having an offset portion above the top, means on the plate below the top for limiting the upward movement thereof, means for connecting the offset portion of the plate to the displaceable member, said plate loosely engaging the wall of the slot to provide a fulcrum support for the displaceable member, and means when the cap is applied to the receptacle for aligning the thumbpiece with the handle.

12. In combination with a receptacle, a one-piece cap, means for detachably connecting the cap to the receptacle, said cap having a discharge opening and a slot in the top thereof, a displaceable member above the top having an end portion constituting a flap normally positioned to close said opening, the opposite end portion of said member being shaped to provide a thumbpiece for actuating the flap, a hinge plate extending through the slot and having an offset portion above the top, means on the plate below the top for limiting the upward movement thereof, means for connecting the offset portion of the plate to the displaceable member, said plate loosely engaging the wall of the slot to provide a fulcrum support for the displaceable member, and a handle connected to the side of the cap and in substantial alignment with said thumbpiece.

13. A cap for dispensing receptacles having a top and a depending skirt, means for detachably connecting the skirt to a receptacle, said top being provided with a spout opening and a diametrically opposed slot, a displaceable member above the top, said displaceable member having an end portion constituting a flap normally positioned to close said spout opening, the opposite end portion of said displaceable member being shaped to provide a thumb piece for actuating the flap, a depending member extending loosely through the slot and having a portion below the top circumscribed by the skirt, means connected

- to the depending member within the cap for limiting the upward movement of the depending member relative to the cap, and means connecting the depending member to the displaceable member above the slot, said depending member coacting with the wall of the slot to constitute a hinged support for the displaceable member.
14. A cap for dispensing receptacles having a top and a depending skirt, means for detachably connecting the skirt to a receptacle, said top being provided with a spout opening and a diametrically opposed slot, a displaceable member above the top, said displaceable member having an end portion constituting a flap normally positioned to close said spout opening, the opposite end portion of said displaceable member being shaped to provide a thumb piece for actuating the flap, a depending member extending loosely through the slot and having a portion below the top circumscribed by the skirt, means connected to the depending member within the cap for limiting the upward movement of the depending member relative to the cap, means connecting the depending member to the displaceable member above the slot, said depending member co-

acting with the wall of the slot to constitute a hinged support for the displaceable member, and yieldable means connected to the depending member below the slot and engaging the underside of the top to maintain normally the flap 5 against the spout opening.

15. A cap for dispensing receptacles having its top provided with a spout opening and a spaced opposed slot, a displaceable member above the top having an end portion constituting a flap normally positioned to close the spout opening, the opposed end portion of the displaceable member extending upwardly and outwardly to provide a thumb piece for actuating the flap, a depending member extending loosely through said slot, said 15 depending member having means below the slot and within the cap arranged to engage the underside of the top to limit the upward movement thereof, and means connecting the depending member to the displaceable member above the 20 top, said depending member coacting with the wall of the slot to provide a fulcrum support for the displaceable member when the latter is moved relative to said spout opening.

CHARLES S. BARON.
